Primary Examiner — Dana L Meyrow(74) *Attorney, Agent, or Firm* — Rutan & Tucker LLP;
Hani Z. Sayed(57) **CLAIM**

The ornamental design for a bottle, as shown and described.

DESCRIPTION

FIG. 1—Bottom, front, left side perspective view of the present invention;

FIG. 2—Front elevation view;

FIG. 3—Rear elevation view;

FIG. 4—Left side elevation view;

FIG. 5—Right side elevation view;

FIG. 6—Top plan view; and,

FIG. 7—Bottom plan view.

The broken line in the FIG. 6 drawing view illustrates the portion of the bottle that forms no part of the claim.

1 Claim, 4 Drawing Sheets(56)
